UNITED STATES PATENT OFFICE

GEORGE W. JARDINE, OF WALTHAM, MASSACHUSETTS

SPRING FOR BED-RIDDEN PATIENTS

Application filed March 19, 1930. Serial No. 437,114.

This invention relates to springs, and an object of the invention is to provide a spring to be placed under a bed-ridden patient, so as to enable the patient to be moved without causing discomfort.

Further objects of the invention are to provide a frame of the character referred to that is strong, compact and durable, very simple in its method of assembly, thoroughly reliable for its intended purpose, and comparatively inexpensive to manufacture and handle.

With the foregoing and other objects in view, the invention consists of a novel construction, combination and arrangement of parts, as will be hereinafter more specifically described and illustrated, in the accompanying drawings wherein is disclosed an embodiment of the invention, but it is to be understood that changes, variations and modifications may be resorted to without departing from the spirit of the claims hereto appended.

In the drawings wherein like reference characters designate like parts corresponding throughout the several views:—

Figure 1 is a plan view of the frame in accordance with the present invention,

Fig. 2 is a side elevation thereof,

Fig. 3 is a vertical, transverse section 30 through the frame,

Fig. 4 is an enlarged fragmentary, detailed horizontal section through the frame,

Fig. 5 is an enlarged horizontal fragmentary detailed section of a portion of one end rail and

Fig. 6 is an enlarged side elevation of one corner of the frame.

Referring to the drawings in detail, 7 indicates generally an open, rectangular frame having side rails 8, 9 connected at their opposite ends to the transversely extensible end rails, indicated generally at 10 and 11. The end rail 10 is formed of two tubular sections, 12, 13 telescopically fitting into each other on confronting ends. Likewise, the end rail 11 is formed of two tubular sections 14, 15 telescopically fitting into each other on confronting ends.

On the outer free end of the female sections 12 and 14, of the end rails, are mounted

T-fittings 16, 17. In the stems 18, 19 of these fittings, are anchored the opposite ends of the one end rail 9, while L-shaped fittings 20, 21 on the outer end of the male sections 13 and 15 form connections with the opposite ends 55 of the other side rail 8 of the frame.

To one branch of the head of the T-shaped fittings 16, 17 is threadably connected the outer end of the female sections 12, 14 of the end rails. The other branch of the T-shaped fittings 16, 17, are open to provide pockets 22 at the corners of the frames to receive the socket wrench 23 for the purpose to be presently described.

Each end rail 10, 11 is extensible in the 65 same manner, and it is believed that the following description of one will clearly teach the operation of the other.

The following description is confined to the end rail 11 of the frame which is clearly 70 illustrated in enlarged views in Figs. 4 and 5 of the drawings. The upper end of the female section 14 that is confined in the one branch of the T-shaped fitting 17, is internally threaded as at 24, to receive a stationary bushing 25 that is provided with an opening 26 through its axis to form a bearing.

The confined inner end of the male section 15 is threaded as at 27 on its inner periphery 80 and is likewise provided with a bushing 28 having a threaded opening 28' through the axis which is in alignment with the opening 26. The operating bolt 29 adjacent its outer end is formed with a smooth round portion 75 30 between shoulders 31, 32 to bear against the opposite ends of the bushing 25.

The smooth portion 30 is rotatably journaled in the opening 26. Above the outer shoulder 31 the shank of the operating bolt 90 29 is formed with a polygonal head 33 seated in the socket 22 and over this head 33 fits a wrench for operating this operating bolt 29.

The major portion of the shank of the operating bolt 29, from its inner end, is provided with threads 34 and the length of this bolt is such that it extends through the threaded opening 28' in the threaded bushing 28. The free end of the bolt is confined 95 in the male section 15 and the length of this 100

bolt is to be such as to provide for the maximum expansion of the frame under ordinary conditions.

Transversely circumscribed about the side rails 8, 9 are a pair of textile fabrics, continuous bands indicated generally at 35, 36, formed of canvas. The opposite ends of each band 35, 36 are spaced inwardly from the end rails 10, 11 while the confronting ends of each band are spaced suitably from each other to provide a pocket 37 therebetween that is co-extensive with the width of the frame.

This space or pocket 37 is located a little to one side of the center longitudinally of the frame, so that a bed pan may be placed under the space to be used by the patient lying on the bands 35, 36. The bands 35, 36 are formed of a single sheet of canvas 38 the ends of which are stitched together as at 39.

In view of the foregoing, it will be seen that I have provided an open, elongated frame, that is transversely extensible, having a band of canvas about the frame with the axis of the band horizontally and at right angles to the extensibility of the frame.

In view of this arrangement, the tension on the canvas band 35, 36 on which the invalidated patient rests, may be made for the comfort of the patient while lying in bed, and in event it is desired to lift the patient bodily, the tension on the bands will draw them taut enough to support the patient while he or she is being carried.

The present embodiment of the invention has been disclosed in considerable detail merely for the purpose of exemplification since in actual practice it attains the features of advantage enumerated as desirable in the statement of the invention and the above description.

It is to be understood that by describing in detail herein any particular form, structure, or arrangement, it is not intended to limit the invention beyond the terms of the several claims, or the requirements of the prior art.

Having thus described my invention, what I claim as new is:—

A bed structure comprising a substantially rectangular frame including side and end bars, said end bars each comprising a male tubular section and a female tubular section telescopically mounted on the male section, said male and female sections each having one end portion internally threaded, said one end portion of the female section also being externally threaded, a bushing threaded in said one end portion of the male section having a threaded bore, a bushing threaded in said one end portion of the female section having a smooth bore, a bolt having a smooth portion journaled in the second named bushing and a threaded portion threaded through the first named bushing, collars fixed on the smooth portion of the bolt engageable with the ends of the second named bushing for re-

taining the bolt against relative longitudinal movement, a T-joint threaded on said one end portion of the female section and having one end of one of the side bars connected thereto, a tool engaging polygonal head on the free end of the smooth portion of the bolt disposed within the T-joint, and flexible fabric extending between the side bars.

In testimony whereof I affix my signature.

GEORGE W. JARDINE.
